CÉSAR COPETTA, OF PARIS, FRANCE, ASSIGNOR OF ONE-HALF TO PAUL JANSSENS DE VAREBEKE, OF WESTMINSTER, ENGLAND.

MEANS FOR SUPPLYING LIQUIDS.

1,335,093.

Specification of Letters Patent. Patented Mar. 30, 1920.

Application filed June 28, 1917. Serial No. 177,615.

To all whom it may concern:

Be it known that I, CÉSAR COPETTA, a citizen of the French Republic, residing at 21 Rue Drouot, Paris, in the Republic of France, have invented certain new and useful Improvements in or Relating to Means for Supplying Liquids, of which the following is a specification.

This invention relates to means for supplying liquids such as means for supplying liquid fuel for engines for various vehicles or vessels although it is capable of general use for supplying other liquids for any purpose. The chief object of the present invention is to provide safe and reliable means for supplying or containing liquids especially in the case of liquid fuel, such as petrol, which means if damaged by accident, or by any enemy rifle or gun fire or the like will not be put out of action or rendered useless but will continue to operate at least for a sufficient length of time to enable the liquid supply to be carried out as desired with safety. The invention may for example be applied to petrol supply means for use on certain types of aeroplanes or airships, the main object being to enable the supply of petrol to the engine to continue with safety even though the petrol tank or container has been penetrated at one or more places by a bullet or shell fragments, so that the pilot may continue flying with safety. A further object is to provide means for indicating that the petrol (or other liquid) tank or container has been pierced, and also for indicating the level of the liquid in the tank after the latter has been pierced, (or at any time) so that (in the case of an aeroplane) the pilot may know whether to continue on his mission or to return to headquarters, or to a place of safety, so as to avoid landing in enemy territory or any other undesired place.

According to this invention I provide a number of separate and independent hermetically closed liquid containers and a common reservoir or feeder open to atmosphere, the containers and the reservoir being so constructed and arranged that the liquid flows from the containers into the reservoir from which latter the liquid is supplied for use and under normal conditions the liquid level in the reservoir is practically constant and automatically controls the flow from the

containers to the reservoir, and in the event 55 of any one or more of the containers being opened to atmosphere the liquid will flow from that container or containers and fill the reservoir until the liquid in being drawn from the reservoir assumes the aforesaid 60 level, so as to control the supply from the unopened containers. The separate liquid containers which may in some cases be conveniently comprised in a single tank, are connected by supply pipes to the common 65 supply reservoir or feeder, which in some cases may be armored, and which is open to atmosphere by means of a tube or tubes or the like extending to a point above the highest liquid level in the containers; this tube 70 or the like may be adapted to serve as a gage or indicator, as hereinafter explained.

When filling the containers, they are open to atmosphere, and the liquid is supplied to one container so as to flow into the common supply reservoir feeder from which latter the liquid flows into the other containers through the supply pipes and into the open tube or tubes. After filling, the various containers are closed to render them air-tight, 75 and the liquid which is under atmospheric pressure owing to the aforesaid open tube or the like is drawn from the feeder so as to first empty the tube; when the liquid reaches a level to uncover the supply pipes from the 80 various containers the liquid flows from the latter and is replaced by air entering through the empty open tube until the liquid again covers the supply pipes. This operation continues automatically, and practically 85 a constant level is maintained in the feeder. In the event of one of the containers being pierced by a bullet the liquid immediately flows from that container into the feeder, filling the latter and also the aforesaid tube or the like to the same level as in the perforated container. When the liquid enters the open tube otherwise than when filling the containers, it will be known that 90 one or more of the containers has been penetrated or opened to atmosphere. The liquid will be supplied from the perforated or opened container until the latter is emptied, when the aforesaid automatic operation 95 takes place.

In order that the said invention may be more clearly understood and readily carried into effect, the same will now be described

more fully with reference to the accompanying drawings, in which:—

5 Figure 1 is a diagrammatic view of one embodiment of the invention showing a vertical axial section of a tank divided into several separate compartments, the armored supply reservoir or feeder being shown in elevation.

10 Fig. 2 is a vertical section of the armored supply reservoir or feeder drawn to an enlarged scale, showing the aforesaid supply pipes connected thereto.

15 Fig. 3 is a horizontal section taken approximately on the line 3—3 of Fig. 2.

20 The tank (Fig. 1) is divided up by partitions into a large number of separate liquid containers or compartments *a*, closed hermetically by cocks *a'* or other devices placed at their upper parts. One of these 25 compartments, however, is fitted with a plug *a²* hermetically closing it, which plug can be removed for filling the tank. From the lower part of each compartment *a*, a supply pipe *b* extends into the interior of a comparatively small common supply reservoir or feeder *c* situated below the tank which 30 feeder may be armored to protect it against bullets; the supply pipe from the compartment closed by the plug *a²* is marked *b'* and will be hereinafter referred to, the neck *c'* of the feeder *c* is hermetically closed for example by a plug *c²* (see Figs. 2 and 3) in or to which the pipes *b*, *b'* are secured. The lower part of the feeder is provided with 35 an outlet pipe *e* leading for example to the carburetor and having a cock or valve *e'* as shown.

40 In the constructional form shown, the lower open ends of the several supply pipes *b*, *b'* are disposed at the same level in the feeder *c*. A tube *d* leading from the feeder *c* but preferably having its lower open end at a level higher than the level of the lower open ends of supply pipes *b* is prolonged 45 externally to a level slightly higher than the highest liquid level in the subdivided tank and establishes communication between the petrol contained in the feeder and the outer air. The tube *d* may be of glass or provided 50 with a glass portion *d'* and may serve as a gage for which purpose it may be graduated. The tube *d* may also be duplicated or formed with one or more branch tubes *d'* one or more of which being of metal for safety. To fill the tank, the plug *a²* is removed and the cocks *a'* are operated to 55 open each compartment to atmosphere; the pipe *b'* leading from the compartment into which the petrol is supplied or poured to the 60 feeder *c*, is preferably of larger bore than the other supply pipes *b* to insure rapid filling. When the feeder *c* is full, the petrol flows up the pipes *b* to fill the various compartments *a*; the petrol will also flow up the 65 tube *d* which, as aforesaid, may serve as a

gage to indicate the level of petrol in the tank. When the various compartments of the tank have been filled, the plug *a²* is replaced and the cocks *a'* are operated to hermetically close the various compartments. 70 When starting the engine the cock *e'* on the pipe *e* leading to the carburetor is opened to allow petrol to flow from the feeder to the carburetor, and the petrol is drawn from the tube *d* which is the only means of communication with atmosphere. Thus the petrol in the feeder is always under atmospheric pressure and the level of the petrol in the feeder is gradually lowered during the working of the engine, until the petrol uncovers the lower ends of the various pipes *b* and *b'* leading from the containers *a* at which time petrol flows from the latter through the pipes *b* and *b'* and is replaced by air entering through the tube *d*. The 75 ends of the pipes *b* and *b'* are again closed or covered by the petrol which has entered the feeder, until the level in the latter is again lowered to uncover the supply pipes when the feeder receives a further supply. 80 Thus the supply of petrol to the feeder is automatically controlled, and the above described operation continues automatically with the result that a practically constant 85 level shown by the line *x*—*x* is maintained 90 in the tank and above the carburetor. During the working of the engine the gage tube *d* is empty, thus showing to the pilot that 95 the tank has not been damaged.

If one (or more) compartments *a* be 100 pierced by a bullet or a shell fragment, the perforated compartment (or compartments) is at once put into communication with the atmosphere. The petrol in the perforated compartment below the perforation flows 105 into the feeder *c*, filling the latter and rising in the gage tube *d* to the level of the petrol in the perforated compartment. The tube *d* which, as aforesaid is preferably of glass 110 enables the pilot to see the petrol appear in this tube, and thus to know that the tank is perforated. The feeder is now only supplied from the perforated compartment and the aforesaid automatic action due to the uncovering and covering of the ends of the 115 supply pipes, is not resumed until the petrol in the feeder has reached its normal level, after all the petrol contained in the damaged compartment or compartments and in the tube *d* has been used, at which time the supply pipes are uncovered to allow petrol from the undamaged compartments to flow into the feeder to recommence the automatic action as aforesaid.

The moment the pilot sees the petrol appear in the glass gage tube, he will as aforesaid know that his tank has been hit (which condition can not be readily ascertained in the case of existing tanks) and he will thus be enabled to take whatever action he re- 120 125 130

gards necessary, either to continue on his journey or return to his place of departure and thus avoid any breakdown due to lack of petrol, and the subsequent forced landing 5 in enemy territory. Considering that in the most unfortunate of circumstances only about one third of the tank is likely to be damaged, there is always enough petrol left for the pilot to continue flying, so that it 10 is not necessary to make a landing in an undesired place. A further advantage is that a constant level of petrol above the carburetor is maintained.

The pilot can at any time ascertain the 15 quantity of petrol contained in the tank, by opening the air cocks a' and thus opening the various compartments to the atmosphere, whereupon the petrol will fill the feeder, and will rise in the graduated glass gage tube d 20 to the level of the liquid in the containers.

When the pilot knows that his tank has been damaged, he will be able to cut off the engine ignition and thus avoid the likelihood 25 of the machine catching fire and falling in flames to the ground. The pilot upon seeing 30 the petrol enter the glass gage, and thus knowing that his tank has just been damaged will at once cut off the ignition until the tube d is empty, which will show him 35 that the escape of petrol outside the tank has ceased. It will then be possible for him to restart the engine, and either proceed on 40 his mission or return to a place of safety.

In no circumstances can the petrol contained 45 in the undamaged compartments flow out through the damaged compartments as the petrol until reaching the level $x-x$ in the feeder covers the outlet apertures of the various supply pipes b or b' .

40 The cocks a' may be operated simultaneously by means of a series of rods, and they may be actuated against a spring or springs normally retaining the cocks closed or the several cocks may be replaced by a 45 multiple way cock. To facilitate the entrance of air into each compartment, a tube d^3 is used which leads from slightly above the level of the petrol in the feeder and provided with branches d^4 opening into the 50 upper part of each compartment. This arrangement of the pipe d^3 with its branch pipes d^4 insures a constant and steady flow of the oil from the containers a to the feeder c , by virtue of the lower end of the pipe d^3 55 being preferably a slight distance above the lower ends of the pipes b . With this arrangement, the liquid flowing from the pipes b into feeder c , having attained a level corresponding to the lower ends of the pipes 60 b , will still continue to flow into the feeder until the lower end of the pipe d^3 has been closed or submerged by the liquid, thus hermetically closing the container. However, 65 it is clear that should the oil be drawn from the feeder c , the lower end of the pipe d^3

will become uncovered and air will be admitted to the containers a to cause a flow to the feeder to replace that which has been withdrawn therefrom; and as soon as the liquid level again rises to the lower end of 70 the pipe d^3 , the containers will again become hermetically sealed and the flow will cease. This action will take place whenever the liquid level in the feeder falls below the lower end of the pipe d^3 . This pipe d^3 with 75 its branches d^4 , may or may not be used in actual practice as may be found desirable.

Although the invention is described more particularly as applied to the petrol supply means on an aeroplane it must of course be 80 understood that it is intended for use for supplying any kind of liquid for any purpose. The invention is especially suitable for use in connection with armored motor vehicles or cycles, motor boats or other vessels in which liquid fuel for internal combustion engines or for oil burners is employed. The invention may also be used in connection with the supply of water for cooling internal combustion engines or for supplying water for steam boilers. 85

What I claim and desire to secure by Letters Patent of the United States is:—

1. Means for supplying liquids, comprising in combination a number of non-communicating containers, a common supply reservoir in communication with said containers and supplied therefrom, said common supply reservoirs being open to the atmosphere at a point above the highest level in the 100 containers.

2. Means for supplying liquids, comprising in combination a number of non-communicating containers, a common supply reservoir in communication with said containers, and a tube leading from the reservoir and extending to a point above the highest level in the containers and open to the atmosphere. 105

3. Means for supplying liquids, comprising a number of non-communicating containers, a common supply reservoir below and in communication with said containers and fed by gravity therefrom, and a member leading from said reservoir open to the atmosphere above the highest liquid level in the containers, said member being adapted to serve as a gage or indicator. 110

4. Means for supplying liquids, comprising in combination a number of separate 120 containers, a common supply reservoir, and separate supply pipes leading from the lower parts of the containers to the reservoir and terminating at the same level therein, the reservoir being open to atmosphere 125 at a point above the highest liquid level in the containers.

5. Means for supplying liquids comprising in combination a number of separate containers, a common supply reservoir, sepa- 130

rate supply pipes leading from the lower parts of the containers to the reservoir and terminating at the same level therein, and an open ended tube extending from the 5 reservoir at a level higher than the level of the ends of said supply pipes to a point above the highest liquid level in the containers.

6. Means for supplying liquids, comprising in combination a number of separate containers, a common supply reservoir, separate supply pipes leading from the lower part of the containers and terminating at the same level in the reservoir, and open 10 ended tubes communicating with the reservoir at a level higher than the ends of the supply pipes to a point above the highest liquid level in the containers, one of said tubes being adapted to form a gage or indicator.

7. Means for supplying liquids, comprising in combination a number of separate hermetically closed containers, a common supply reservoir, separate supply pipes leading from the lower parts of the containers and terminating at the same level in the reservoir, an open ended tube extending from the reservoir at a point above the level of said supply pipes to a point above 25 the highest liquid level, and connections whereby each container can be opened to atmosphere when desired.

8. Means for supplying liquids, comprising in combination a number of separate hermetically closed containers, connections whereby each container can be opened to atmosphere when desired, a common supply reservoir, separate supply pipes leading from the containers to the reservoir and a 30 member extending from the reservoir and open to the atmosphere at a point above the highest liquid level in the containers and said member forming a gage or indicator.

9. Means for supplying liquids, comprising in combination, a tank divided into a 45 number of separate compartments, and a comparatively small supply reservoir below the tank in communication with said separate compartments and open to atmosphere 50 at a point above the highest liquid level in the said compartments.

10. Means for supplying liquids, comprising in combination a tank divided into a number of separate compartments, a comparatively small common supply armored reservoir, separate supply pipes leading from the said compartments to the reservoir and terminating at the same level therein and an open ended tube or tubes communicating with the reservoir at a level above the 55 level of the ends of said supply pipes to a point above the highest liquid level in the said compartments, one of said tubes being adapted to serve as a gage or indicator.

65 11. Means for supplying liquids, comprising

ing in combination a tank divided into a number of separate hermetically closed compartments, a comparatively small common supply armored reservoir, separate supply pipes extending to said reservoir 70 which is open to atmosphere at a point above the highest liquid level in said compartments, and connections whereby the compartments may be opened to atmosphere when desired.

75 12. Means for supplying liquids, comprising in combination, a tank divided into a number of separate hermetically closed compartments, connections whereby the compartments can be opened to atmosphere 80 when desired, a common supply armored reservoir, separate supply pipes leading to said reservoir and terminating at the same level therein, a tube or tubes communicating with said reservoir at a point above the 85 level of the ends of the supply pipes and open to atmosphere at a point above the highest liquid level in the compartments one of said tubes being adapted to serve as a gage or indicator.

90 13. In a device of the character described comprising a plurality of non-communicating containers, a reservoir fed by gravity from said containers, and means for indicating when one of said containers has been 95 punctured and for giving the liquid level in the remainder of said containers.

14. In a device of the character described, a number of non-communicating containers arranged at one level, a common supply 100 reservoir below the containers and in communication therewith and supplied by gravity therefrom, an extension provided on said reservoir and open to the atmosphere at a point above the highest liquid level in the 105 containers, said extension acting as means for indicating when one of said containers has been punctured and for giving the oil level in said containers, and means for permitting the liquid level of the containers to 110 be ascertained at will.

115 15. A device of the kind described comprising a plurality of normally closed containers, a common supply reservoir, pipe connections between the containers and reservoir for supplying liquid by gravity to the latter, the normal liquid level in the reservoir hermetically closing the containers, and an indicator tube extending from the reservoir at a point above the normal liquid 120 level therein to a point substantially above the highest liquid level in the containers, whereby when one or more of said containers has been punctured the reservoir will be flooded and the indicator tube will indicate 125 the condition of the device.

16. Means for supplying liquids, comprising in combination a number of separate containers, a common supply reservoir in communication with said containers and 130

automatically fed by gravity therefrom, said reservoir being open to atmosphere at a point above the highest liquid level in the containers.

- 5 17. A device of the kind described, comprising a normally closed container, a feeder open to atmosphere and disposed below the container and fed by gravity therefrom, a supply pipe between the container and 10 feeder and having its lower end terminating at a point within the feeder whereby the liquid supplied to the feeder will rise to a level to close the lower end of said pipe, and another pipe communicating with said container above the liquid level therein and terminating within the feeder at a point above the lower end of said supply pipe to be closed by the normal liquid level in the feeder said second pipe being adapted 15 to automatically supply air to the container

when the liquid level of the feeder is below normal.

18. Means for supplying liquids, comprising in combination a number of non-communicating containers, a common supply reservoir below said containers and fed by gravity therefrom, supply pipes leading from the lower parts of the containers to the reservoir and terminating at the same level therein, pipes communicating with said containers above the liquid level therein and terminating within the reservoir at a point above the lower end of said first pipes, said second pipes being adapted to automatically supply air to the containers when the liquid level of the reservoir is below normal, and a member leading from said reservoir and open to the atmosphere above the highest liquid level in said containers. 25 30 35

CÉSAR COPETTA.
